UNITED STATES PATENT OFFICE

2,519,771

CHIROPODIST'S WASTE RECEPTACLE

Ernest H. Lacore, Torrington, Conn.

Application October 10, 1947, Serial No. 779,018

3 Claims. (Cl. 155—165)

1

This invention relates to waste receptacles, and more particularly to a receptacle adapted to be supported on a chiropodist's chair in a position convenient to receive waste incidental to the work of a chiropodist.

One object of this invention is to provide a receptacle of the above nature including a guide bracket adapted to be permanently attached to the foot rest of a chiropody chair, and a waste-receiving pan removably supported by said bracket.

Another object is to provide a device of the above nature in which the pan has a capacity sufficient to allow waste to be conveniently deposited therein.

Another object is to provide a device of the above nature having a pan which is readily removable and replaceable, whereby the operations of emptying and sterilization are facilitated.

Another object is to provide a device of the above nature which will be securely supported in convenient relation to the adjustable foot rest of the chair, and which will not interfere with the adjustment or use of the chair.

A further object is to provide a device of the above nature which will be simple in construction, inexpensive to manufacture, easy to install and manipulate, compact, ornamental in appearance, and very efficient and durable in use.

With these and other objects in view, there has been illustrated on the accompanying drawing one form in which the invention may conveniently be embodied in practice.

In the drawings,

Fig. 1 is a perspective view of a chiropody chair having the improved waste receptacle attached thereto.

Fig. 2 is an exploded perspective view of the waste pan, the guide bracket, and a portion of the footrest bracket.

Fig. 3 is a fragmentary cross sectional view, taken through one edge of the waste pan and the guide bracket.

Referring now to the drawings in which like reference numerals denote corresponding parts throughout the several views, the letter R indicates generally the improved waste receptacle which is substantially rectangular in shape and is adapted to be attached to any conventional chiropody chair C having a foot rest F.

An upstanding U-shaped bracket 10 pivotally supports the foot rest F at its upper ends and is provided with a slotted link 11 and a clamp screw 12, whereby the foot rest may be held in any desired adjusted position with respect to its piv-

2

otal connection to the bracket 10. The lower part of the bracket 10 includes a horizontal bar 13 mounted on the chair C by means of a pair of vertical telescoping guide rods 14 provided at their upper ends with axial end screws 15 passing through apertures 16 in the bar 13 for clamping the bracket 10 thereto. An adjusting screw 17 serves to support the bracket 10 in any desired vertical position.

10 The waste receptacle R comprises a substantially rectangular pan 18 adapted to be carried by a rectangular guide bracket 19, the rear edge portion of which has apertures 20 in alignment with the apertures 16 of the bar 13, for receiving 15 the end screws 15 in order to clamp the bracket 19 firmly upon the chair C.

The bracket 19 is preferably of a width to fit between the upstanding arms of the bracket 10 and is formed of stiff sheet material such as stain- 20 less steel, or any suitable plastic. The side edges of the bracket 19 are bent upwardly and inwardly to provide a pair of guides 21 which cooperate with the bottom of the bracket 19 to form guide 25 channels 22. The pan 18 is generally flat and has rounded front corners 23, and a vertical wall 24 extending upwardly around its periphery.

The pan 18 is of a width to fit between the rails 21 and includes horizontal side flanges 25 projecting outwardly from the lower side edges of 30 the rear portion of said pan. The flanges 25 preferably are provided by flat strips 26 secured to the outer bottom surface of the pan 18 as by welding or soldering 27, and are adapted to be received snugly in the channels 22 of the guide bracket 19 in order to support the pan firmly 35 and removably in place.

Operation

40 The improved chiropodist's waste receptacle may be installed during the assembly of the chair C simply by applying the rectangular guide bracket 19 to the upper side of the horizontal bar 13 and passing the screws 15 through the aligned apertures 16 and 20 into the upper ends 45 of the supporting rods 14.

If the chiropodist's chair C has already been 50 assembled, the receptacle may be easily applied thereto merely by removing the screws 15, inserting the guide bracket 19 between the arms 55 of the U-shaped bracket 10, and reapplying the screws 15 through the apertures of the guide bracket 19 and the horizontal bar 13. The screws 15 will then hold the bracket 19 firmly in a horizontal position whereby the pan 18 may be supported in the channels 22.

It will be seen that the waste receptacle is supported in a position convenient to the chiropodist while he is treating the feet of a patient seated in the chair, and is vertically adjustable along with the foot rest, so that it will always occupy substantially the same position with relation to the feet of the patient.

One advantage of the present invention is that the pan 18 will be easy to empty merely by pulling it outwardly to disengage the flanges 25 from the channels 22, whereupon the contents may be dumped into any suitable receiver.

Another advantage is that the flat strips 26 provide bearings or "shoes" whereby the pan will slide smoothly upon the guide bracket 19.

The improved chiropodist's waste receptacle is of simple construction, and may be easily sterilized.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a chiropody chair, a foot rest, means supporting said foot rest comprising a U-shaped bracket attached to said foot rest and having a horizontal bar below said foot rest, and a waste receptacle including a horizontal guide bracket having channelled side edges, said guide bracket having an apertured rear edge secured to said

bar, and a pan having side flanges received in said channelled side edges, whereby the pan will be slidably supported on said foot rest supporting means by said guide bracket.

5 2. The invention as defined in claim 1, in which said foot rest supporting means includes a mounting element, and a screw securing said horizontal bar to said mounting element, said screw passing through an aperture of said guide bracket to clamp said bracket against the upper face of said horizontal bar.

10 3. The invention as defined in claim 1, in which said first bracket includes arms upstanding from the ends of said horizontal bar, and the apertured rear edge of the guide bracket is disposed upon the upper surface of said bar between said arms, and a screw securing said apertured edge against said bar.

15 ERNEST H. LACORE.
